UNITED STATES PATENT OFFICE

157,508

FLEXIBLE SPRAY BOTTLE

Jules B. Montenier, Chicago, Ill.

Application March 25, 1949, Serial No. 1,609

Term of patent 14 years

(Cl. D58—9)

To all whom it may concern:

Be it known that I, Jules B. Montenier, a citizen of the United States, residing at Chicago, in the county of Cook and State of Illinois, have invented a new, original, and ornamental Design for a Flexible Spray Bottle, of which the following is a specification, reference being had to the accompanying drawing, forming a part thereof.

In the drawing—

Fig. 1 is a front elevational view of a flexible spray bottle, showing my new design;

Fig. 2 is a side elevational view thereof; and

Fig. 3 is a top plan view thereof.

The essential features of my design reside in the portions shown in full lines in the drawing, consisting of the specific form of ornamentation applied to a bottle as shown in the drawing.

I claim:

The ornamental design for a flexible spray bottle, as shown and described.

JULES B. MONTENIER.
